(57) **CLAIM**

The ornamental design for a packaging box for mobile phone, as shown and described.

DESCRIPTION

FIG. 1 is a perspective view of a packaging box for mobile phone showing my new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a bottom perspective view showing the state in which the outer cover has been closing;

FIG. 8 is a perspective view thereof showing the state in which the inner cover of the packaging box for mobile phone has been open;

FIG. 9 is a front view of FIG. 8;

FIG. 10 is a rear view of FIG. 8;

FIG. 11 is a left side view of FIG. 8;

FIG. 12 is a right side view of FIG. 8;

FIG. 13 is a top plan view of FIG. 8; and,

FIG. 14 is a bottom plan view of FIG. 8.
